UNITED STATES PATENT OFFICE.

WILLIAM IILE, OF JACKSON, MICHIGAN, ASSIGNOR TO REYNOLDS SPRING COMPANY,
OF JACKSON, MICHIGAN, A CORPORATION OF DELAWARE.

CAP AND SHELL FASTENING FOR LAMP-SOCKET CASINGS.

Application filed July 2, 1925. Serial No. 41,208.

The invention relates to a cap and shell fastening for lamp socket casings.

The object of the present invention is to provide a simple, practical and efficient cap and shell fastening of strong, durable and comparatively inexpensive in construction capable of enabling a cap to be easily and quickly applied to a shell and of securely fastening the cap thereon, and of also permitting the ready removal of the cap when desired.

A further object of the invention is to provide a cap and shell fastening of this character in which the coacting fastening means on the shell will not impair the strength and durability of the same and thereby afford a lamp socket casing of this character having a shell of maximum strength and durability.

With these and other objects in view, the invention consists in the construction and novel combination and arrangement of parts hereinafter fully described, illustrated in the accompanying drawing and pointed out in the claim hereto appended, it being understood that various changes in the form, proportion and minor details of construction, within the scope of the claim, may be resorted to without departing from the spirit or sacrificing any of the advantages of the invention.

In the drawing:

Figure 1 is a perspective view of a lamp socket casing constructed in accordance with this invention, the cap being shown separated from and elevated above the shell or body portion of the casing.

Fig. 2 is a vertical sectional view of the same the cap being shown separated from the body portion or shell and properly positioned with relation thereto for interlocking the cap with the shell.

Fig. 3 is a similar view the cap and shell being interlocked.

Fig. 4 is a horizontal sectional view of the same.

In the accompanying drawing in which is illustrated the preferred embodiment of the invention 1 designates the metallic shell or body portion of the lamp socket casing provided at its upper end which is telescopically engaged by the flange 2 of the cap 3 with equally spaced grooves of substantially uniform width located at diametrically opposite points and arranged to slidably receive interiorly arranged projections 4 of the

cap 3. Three of the grooves designated by the numeral 5 are approximately L-shaped or bayonet shaped and consist of vertical entrance branches 6 and horizontal branches 7 while the fourth groove 8 is vertical. The cap is adapted to be telescopically fitted over the upper end of the shell and the projections 4 are formed by indenting the metal of the flange 2 from the exterior to provide interior projections or protuberances integral with the cap. These interior projections or protuberances are adapted to fit and slide in the vertical branches 6 of the L-shaped grooves 5 and in the vertical groove 8 by a telescopic movement of the cap with relation to the shell. After the cap has been moved telescopically over the shell to the inner ends of the vertical branches 6 of the grooves 5 and the inner end of the groove 8, the cap is partially rotated to the left to carry the projections 4 into engagement with perforations 9 and 10. The perforations 9 and 10 are equally spaced and are of a size to receive the projections 4. The perforations 9 are located adjacent to the outer ends of the horizontal branches 7 of the grooves 5 while the perforations 10 are located adjacent the vertical groove 8. The perforations 9 and 10 are equally spaced from the vertical branches 6 and the vertical groove 8 so that the projection will be carried by relative rotary movement of the parts into engagement with the perforations 9 and 10. Any one of the perforations may be fitted in any one of the grooves so that it is not necessary to arrange the cap in any particular position with relation to any particular groove, it being only necessary to position the projections so that they will enter the grooves. The perforation which engages the groove 10 moves over an imperforate portion of the shell which is not indented or depressed at the perforation 10 so that the projection and perforation 10 will form a lock for holding the parts against relative rotary movement, it being necessary to depress or compress the shell at the perforation 10 to disengage the same from the projection of the cap when it is desired to remove the latter. To facilitate the easy compression of the shell the latter is provided adjacent the vertical groove 8 with a slit or kerf 11. The outer ends of the branches 7 of the grooves 5 indent or depress the metal of the shell at the perforations 9 so that the pro-

jections fitting in the perforations 9 may be readily moved out of the same and will slide in and out of the perforations by a relative rotary movement of the parts without resistance when the locking device formed by the perforation 10 in one of the projections does not interfere with such relative rotary movement. The projections will engage the metal of the shell at the tops of the perforations 9 as well as at all points except where the metal is depressed at the horizontal branches of the grooves 5 and when the cap is fitted on a shell in interlocked relation therewith, a strong structure will be provided and the cap and shell will resist material strain tending to separate the parts.

What I claim is:

A cap and shell fastening for lamp socket casings, comprising a shell provided at the upper end with a plurality of equally spaced grooves, one of the grooves being substantially vertical and enclosed at the lower end and the other grooves being approximately L-shaped and consisting of a vertical en-

trance branch and a horizontal branch, said shell being also provided with perforations spaced equally from the vertical entrance branches and the vertical grooves, the perforations of the L-shaped grooves being arranged at the extremity of the horizontal branches and forming extensions thereof, and providing openings at the terminals of the horizontal branches, and a cap provided with interior projections slidable in the grooves by telescopic movement of the cap over the shell; and adapted to be carried into the perforations by relative rotary movement of the cap and shell, said projections being of a diameter equal to the width of the grooves and to the diameter of the openings and the projection engaging the perforation adjacent the vertical groove forming a positive lock for holding the cap and shell against relative rotary movement.

In testimony whereof I have hereunto set my hand.

WILLIAM ILE.
